CLAIM

The ornamental design for a burger preparation utensil, as shown and described.

DESCRIPTION

FIG. 1 is a perspective view of the top side of a burger preparation utensil, shown in the closed position.

FIG. 2 is a perspective view of the utensil of FIG. 1 shown in the open position.

FIG. 3 is a side view of the utensil of FIG. 1.

FIG. 4 is the opposing side view of the utensil of FIG. 3.

FIG. 5 is an end view of the utensil of FIG. 1, from the handle end.

FIG. 6 is the opposing end view of the utensil of FIG. 5.

FIG. 7 is a topside view of the utensil of FIG. 1; and,

FIG. 8 is a bottom side view of the utensil of FIG. 1.
